United States Patent Office

Des. 176,869
Patented Feb. 7, 1956

176,869

GARGOYLE

Michael Ksenak, Gary, Ind.

Application August 8, 1955, Serial No. 37,355

Term of patent 14 years

(Cl. D13—1)

Fig. 1.

I claim:

The ornamental design for a gargoyle, as shown.
